(57) **CLAIM**

The ornamental design for rail mount bracket, as shown and described.

DESCRIPTION

FIG. 1 is a front, top, and left side perspective view of a rail mount bracket, showing my new design.

FIG. 2 is a front, top, and right side perspective view thereof.

FIG. 3 is left side elevation view thereof.

FIG. 4 is a right side elevation view thereof.

FIG. 5 is a front elevation view thereof.

FIG. 6 is a rear elevation view thereof.

FIG. 7 is a top plan view thereof; and,

FIG. 8 is a bottom plan view thereof.

The dash-dash lines depict portions of the rail mount bracket that form no part of the claimed design.
